UNITED STATES PATENT OFFICE.

FRED S. BEACH AND FITCH H. BEACH, OF CHARLOTTE, MICHIGAN.

KNOCKDOWN CULVERT.

No. 889,745.

Specification of Letters Patent.

Patented June 2, 1908.

Application filed September 6, 1905. Serial No. 277,168.

To all whom it may concern:

Be it known that we, FRED S. BEACH and FITCH H. BEACH, citizens of the United States, residing at Charlotte, in the county of Eaton and State of Michigan, have invented a new and useful Knockdown Culvert, of which the following is a specification.

This invention relates to certain improvements in sectional culverts of that general class designed for use beneath rail-way tracks, road-ways and the like or in the construction of sewers, conduits and similar structures.

The object of the invention is to provide a strong durable culvert of this character capable of being set up for use without the employment of skilled labor and one in which the several culvert sections may be quickly disconnected and compactly nested for transportation or shipment.

20 A further object of the invention is to form the culvert of a plurality of circumferentially corrugated sections each section of which is provided with a plurality of spaced locking lugs which alternately engage 25 the interior and exterior wall of an adjacent section when the several sections are assembled.

A still further object of the invention is to generally improve this class of devices so as 30 to increase their utility, durability and efficiency as well as to reduce the cost of manufacture.

Further objects and advantages will appear in the following description, it being 35 understood that various changes in form, proportions and minor details of construction may be resorted to within the scope of the appended claims.

In the accompanying drawings forming a 40 part of this specification: Figure 1 is a perspective view of a portion of a culvert constructed in accordance with our invention. Fig. 2 is a transverse sectional view of the same. Fig. 3 is a longitudinal sectional view 45 taken on the line 3—3 of Fig. 1. Fig. 4 is a side elevation showing the locking tongues extended approximately the width of three of the circumferential corrugations.

Similar numerals of reference indicate corresponding parts in all of the figures of the drawings.

The sections 5 are preferably constructed of corrugated sheet metal bent or otherwise formed into semi-cylindrical shape, as shown, 55 said sections having their longitudinal edges provided with a series of marginal notches

or recesses 6 defining a plurality of spaced locking lugs 7.

The locking lugs 7 are alternately off set or bent inwardly from the longitudinal edges of the sections 5 so that when the several sections comprising the culvert are assembled the lugs on one section will interlock with the lugs on an adjacent section and alternately engage the interior and exterior walls of said sections thereby to reinforce and strengthen the walls of the culvert and effectually prevent the same from spreading laterally when subjected to downward pressure, while at the same time permitting the several sections to expand upwardly when the water in the culvert freezes.

By having the several sections constructed in the manner described the culvert may be conveniently set up for use and the several culvert sections quickly detached and compactly nested for transportation or shipment.

Attention is here called to the fact that by having the interlocking lugs alternately off set or disposed in staggered relation the lugs of one section will exert a spring clamping action on the walls of an adjacent section and thereby assist in retaining the several sections in assembled position. It will also be observed that the locking lugs on each culvert section are curved transversely to conform to the circumferential corrugations of an adjacent section and with which they interengage so as to form in effect an auxiliary lock and thus assist in preventing longitudinal movement of the individual sections, as best shown in Fig. 3 of the drawings.

By curving the lugs transversely to conform to the circumferential corrugations of the culvert sections, said lugs also act as guides so as to permit the several sections to be readily assembled.

In Fig. 4 of the drawings there is illustrated a modified form of the invention in which the locking lugs are of a width approximately equal to three of the circumferential corrugations, the construction of the culvert being otherwise similar to that shown in Fig. 1 of the drawings.

From the foregoing description it will be seen that there is provided an extremely simple, inexpensive and efficient device admirably adapted for the attainment of the ends in view.

Having thus described the invention what is claimed is:

A knock down culvert including a plu-

2

rality of substantially semi-cylindrical, circumferentially corrugated sections having their opposite longitudinal edges provided with spaced recesses defining intermediate locking lugs adapted to engage the lugs of an adjacent section when the several sections are assembled to form a culvert, said lugs being curved transversely to conform to the circumferential corrugations of an adjacent section with their free ends alternately offset, said sections being arranged to break joint with the lugs on one section engaging the lugs of two adjacent sections and with the

transversely curved portions of the lugs bearing against the circumferential corrugations on the interior and exterior walls of said sections.

In testimony that we claim the foregoing as our own, we have hereto affixed our signatures in the presence of two witnesses,

FRED S. BEACH.
FITCH H. BEACH.
